SEAL

George G. Canter, New York, N. Y.

Application October 6, 1949, Serial No. 119,900

5 Claims. (Cl. 292—317)

1

This invention relates to seals, more particularly to strap seals of the type suitable for use on freight cars, trucks and containers of various kinds for the shipment of valuable goods, which is removable only by destruction.

The present invention relates to improvements in the seal described in my co-pending application Serial No. 60,603, filed November 17, 1948. The said application describes a seal comprising a closure made of two permanently joined shells with a slot in one of the shells, a separate slotted disk secured between the shells and a strap, one end of which passes through a slot in the washer and is bent over and permanently secured to the inner face of the washer by means of a rivet. The rivet may be separate or may be formed integrally with the disk or the strap end may be fastened to the disk by means of a weld.

One of the principal objects of the present invention is to avoid the use of a separate disk together with its separate fastening means to cheapen and simplify the construction and assembly of the seal.

Another object is to provide improved fastening of the strap end which is permanently secured in the enclosure, at the same time reinforcing the improved form of disk with the result that it may be made of the lighter metal from which the strap is made and as an integral part thereof.

Another object is to eliminate the need for riveting or welding, thus saving another step in the manufacture.

A still further object is to provide a guide serving to direct the free end of the strap into the slot of the disk without adding to the cost of construction.

The invention will best be understood from the following description of the present preferred embodiment thereof, taken in conjunction with the drawings in which:

Fig. 1 is a plan view of the complete seal as supplied to the user;

Fig. 2 is a plan view of the sheet-metal blank with the various slots, tongues and guiding member formed therein;

Fig. 3 is a side elevation of the blank as seen from the left side of Fig. 2;

Fig. 4 is a perspective view of the head of the blank partially bent to its final shape and Fig. 5 shows the head after the completion of the bending;

Fig. 6 is an elevation of the end of the strap as shown in Fig. 5 inserted in the lower shell of the enclosure, which is shown in central section;

Fig. 7 is a similar view taken at right angles to

2

the view of Fig. 6 and shows the upper shell in place and fastened to the lower shell;

Fig. 8 is an enlarged central section through the strap end taken on the line 8—8 of Fig. 5 and 5 showing the free end of the strap entering the slot in the disk;

Fig. 9 is a similar view showing the free end of the strap in fully inserted locking position; and

Fig. 10 shows the deformation of the interlocked ends of the strap produced by a force tending to pull the free end out of its locked position.

The seal consists of only three principal parts namely: An elongated strap 14 with parallel sides made of sheet metal having a slight springiness, such as quarter-hard cold rolled steel about .015" thick, a lower sealing shell 15 and an upper sealing shell 16. The strap 14 may be embossed with the user's designation and a serial number in the usual way, as shown in Fig. 1.

20 Referring to Figs. 2 and 3, the strap is stamped out of sheet metal in the form shown with an integral, substantially circular disk 18 having a central elongated slot 19, the material punched

25 out of the slot, which is cut only on three sides, forming a reinforcing and guiding rib 20 which is turned back at slightly less than a right angle to the adjacent side of the disk. Joining the disk 18 at the lower uncut portion of its periphery is a substantially semicircular head 21 terminating

30 in a narrower straight-sided portion 22 which is somewhat wider than the body of the strap 14 so as to provide shoulders 24. A tongue 25 is punched out of the portion 22 having its root in line with the junction between the head 21 and portion 22. The other end of strap 14 is provided with a tongue 26 which extends toward the head of the strap and is pressed outwardly at a slight angle thereto on the same side as the tongue 25.

35 The head of this strap is then bent as shown 40 in Figs. 4 and 5 so that the semicircular head 21 extends at right angles to the strap, which brings the tongue 25 into an upstanding position as shown in Fig. 4, and the disk 18 is bent downwardly into contact with the head portion 21 with the tongue 25 extending upwardly through the slot 19 in the disk 18. The strap member as thus

45 formed is then dropped into the lower shell 15 which is provided with a slot 28 through which the strap 14 passes. Slot 28 is slightly narrower than the bottom of the shell. The folded head of the strap rests on the circular shoulder 29 of the shell and the shoulders 24 at the bottom of the portion 22 rest on the bottom of the shell at either end of the slot 28. The upper flanged shell 16 is then placed in position and the rim of shell

15 is crimped over the rim of shell 16 as shown in Fig. 7, completing the assembly of the seal.

The operation of the seal is illustrated in Figs. 8, 9 and 10. Fig. 8 shows the free end of the seal starting its passage upwardly through the slot 19 in the disk and it will be noted that the rib 20 acts to guide it into this slot. Fig. 9 shows the strap end moved past the tongue 25, which snaps into the slot in the free end of the strap produced by punching out the tongue 26. Once the tongue 26 has passed beyond the tongue 25, the free end of the strap is locked and cannot be withdrawn. If it is pulled in the direction tending to withdraw it, the parts move into the position shown in Fig. 10 in which the tongue 25 is drawn downwardly over the slot 19 and the tongue 26 bends against the top of the disk 18, across which it slides, thus locking the ends of the strap together more securely.

It will be noted that although the disk 18 is made of the relatively thin metal of the strap body, the folded construction provides a substantial reinforcement of the disk in that one-half of the disk is in effect of double thickness due to the fact that the semicircular head portion 21 underlies it and rests on the flange of the shell 15. It is this portion of the disk which receives the pressure from the tongue 26 if an attempt is made to pull out the free end of the strap. The disk is further supported approximately across its center by the portion 22 which rests on the bottom of shell 15. The rigidity of disk 18 is further assured by the downwardly-turned flange 20 which also acts to guide the strap end as it comes up through the slot 20 in the shell toward the slot 19 in the disk.

The invention thus provides a seal of the type described which is positive and sure in action, not likely to be rendered inoperative by accidental damage, and cannot be opened after once being engaged without leaving obvious signs of tampering. Furthermore, the seal can be made and assembled inexpensively by reason of the simplicity of its parts.

In view of obvious modifications which may be made in the embodiment herein particularly described without departing from the spirit of the invention it is to be construed broadly within the purview of the claims.

What is claimed is:

1. A seal comprising an enclosure formed by a pair of shells permanently secured together, a slotted disk extending across said enclosure and secured between said shells, one of said shells having a slot aligned with the slot in the disk, an elongated strap having a body and an integral head portion bent at an angle to the body of the strap and formed integrally with said disk, said disk and said head portion being folded together, a tongue projecting angularly across said slot in the disk on the opposite side of the disk from the strap body, the other end of the strap having a slot adapted to receive said tongue when said other end is pushed through said slot in the disk.

2. A seal comprising an enclosure formed by a pair of shells permanently secured together, a slotted disk extending across said enclosure and secured between said shells, one of said shells having a slot aligned with the slot in the disk, an elongated strap having a body and an integral head portion bent at an angle to the body of the strap and formed integrally with said disk, said

disk and said head portion being folded together, a tongue projecting from the margin of said head portion through the slot in the disk so as to extend angularly across said last mentioned slot, the other end of the strap having a slot adapted to receive said tongue when said other end is pushed through the slot in the disk.

3. A seal comprising an enclosure formed by a pair of shells permanently secured together, a slotted disk extending across said enclosure and secured between said shells, one of said shells having a slot aligned with the slot in the disk, a strap having an elongated body and an integral head portion bent at an angle to the body of the strap and formed integrally with said disk, said disk and said head portion being folded together, said strap having a portion between said head portion and its body wider than the slot in said shell with shoulders resting on said shell, a tongue projecting through the slot in the disk so as to extend angularly across said last mentioned slot, the other end of the strap having a slot adapted to receive said tongue when said other end is pushed through the slot in the disk.

4. A seal comprising an enclosure formed by a pair of shells permanently secured together, a slotted disk extending across said enclosure and secured between said shells, one of said shells having a slot aligned with the slot in the disk, a strap having an integral head portion bent at an angle to the body of the strap and formed integrally with said disk, said disk and said head portion being folded together, a tongue projecting angularly across said slot in the disk, the other end of the strap having a slot adapted to receive said tongue when said other end is pushed through said slot in the disk, the slot in said disk being formed by cutting three sides of the opening and bending the material defined by the cut at an angle to the disk on the side toward the slot in the shell to form a reinforcing and guiding rib.

5. A seal comprising an enclosure formed by a pair of circular flanged shells permanently secured together, a strap having an integral semicircular head portion bent at a right angle to the body of the strap, an integral circular slotted disk having a common margin with said head portion, said disk and said head portion being folded together, a tongue projecting from the margin of said head portion through the slot in the disk so as to extend angularly across said slot, said head portion and said disk being secured between said shells so as to form a partition in said enclosure, one of said shells having a slot aligned with the slot in the disk through which the strap passes, the other end of the strap having a slot adapted to receive said tongue when said other end is pushed through the slot in said disk.
